PROPORTIONAL CYCLING SWITCH

Jurg A. Senn, Washington, D. C.

Application August 1, 1945, Serial No. 608,167

12 Claims. (Cl. 200—136.3)

1

This invention relates to cycling switches adapted to automatically supply electric power to using devices at varying time intervals and more specifically to those in which the length of the On and Off cycles depends on both the actual temperature and the desired temperature.

Gouy in the French publication: *Journal de Physique* 6, 479 (1897) describes a thermoregulator in which a platinum wire is extended downwardly into contact with the mercury meniscus of a U-tube which is closed at one end and thus serves as a temperature indicator. The platinum wire is oscillated vertically by an off-center cam into and out of the mercury to control the energization of the electric heating circuit for the temperature indicator. The connection to his heater is such that energy is periodically supplied to the bath during that part of the cycle of motion of the platinum wire during which the latter is not in contact with the mercury. An increase in the temperature of the mercury bulb results in the meniscus rising which causes a decrease in the length of time during which energy is periodically supplied to the bath, thus tending to stabilize the bath temperature.

One of the most serious objections to Gouy's off-center cam type of switch contact actuator is the variable spacing of the contacts in their open position. This is most objectionable when the platinum wire is withdrawn from the mercury meniscus for such a slight distance that the circuit across the contacts is not opened but continues as an arc, burning and pitting the contacts. In Gouy this variation in the spacing of the contact surfaces due to burning does not change the adjustment since one of the contacts (mercury) is a part of the temperature-responsive element. In disc or button-contact switches using the Gouy arrangement, however, contact spacing is one of the factors affecting temperature calibration and any reduction of this space necessitates recalibration of the device.

Since the eccentricity of the cycling cam should be large as compared with the movement necessary to make or break the power contacts, and the energy distribution along the cyclic cam excursions should be as large as possible in order that great stabilizing range and close regulation may be obtained under a wide range of external heat transfer conditions, a relatively large diameter cam is required with the Gouy system which is objectionable where space is limited.

In Gouy's scheme contact with the moving platinum wire must be made in the form of a flexible lead or pigtail. Such leads are to be avoided

2

wherever possible due to the risk of shorting through broken insulation, breakage due to excessive twisting, etc. The present invention eliminates each of the foregoing disadvantages and in addition provides further advantages which will be described.

Therefore, it is an object to provide a cyclic switch operating on the Gouy principle but modified to provide contacts in which the make and break travel is uniform over the entire range of operation of the switch.

Another object is to provide a switch of the character specified in which variations in the thickness of the contacts due to wear, pitting, burning or other cause does not affect the calibration of the switch.

A further object is to provide a cyclic switch of the character specified in which the range of stabilizing regulation is not dependent on the eccentricity of an off-center cam, but instead is limited only by the dimensions of a cylindrical cam, thereby greatly increasing the On-Off, or stabilizing range and making the switch more compact.

Another object is to provide a proportional, cycling switch utilizing the Gouy principle in a superposed, spring-biased lever system which is virtually free of lost motion or deformation of the parts over a long, switch-operating life.

A further object is to provide a proportional, cycling switch utilizing the Gouy principle in a multiple lever system that is protected from excessive biasing forces by a tensioned, follow-up spring.

Another object is to provide a switch of the character specified having a multiple lever system in which the biasing action of the temperature indicating means as well as that of the temperature setting cam is applied close to the fulcrum of the main lever, thereby lessening the risk of deformation of the levers and consequent inaccurate temperature responsiveness of the switch.

Another object is to provide a proportional, cycling switch utilizing a peripheral, circular, disc-cam as the temperature adjustment means thereby obtaining virtually 360 degrees of adjustment in stepless, straightline or other pattern of control as desired.

Another object is to provide a switch of the character described that is inexpensive and is easily manufactured, assembled and adjusted.

Further objects and advantages will be apparent as the description proceeds.

Reference is now made to the drawing wherein

Fig. 1 is a plan view of a preferred form of cyclic switch embodying the principles of my invention, partly broken away along the line 1—1 of Fig. 2, the switch contacts being omitted for clarity and the cycling cam lever shown partly broken away;

Fig. 2 is a sectional view of my switch taken on the line 2—2 of Fig. 1, the switch contacts and their carrier being shown in elevation and the cycling cam lever of Fig. 1 being shown in its operative relation to the cycling cam; and

Fig. 3 is an end, sectional view of my improved switch taken on the line 3—3 of Fig. 1, the switch contacts and the carrier thereof being shown in elevation.

In the drawing there is shown at 1 a box-like, outer housing on one wall of which is mounted by means of screw 2 and nut 3, a circular cam-disc 4 having an inclined periphery providing a cam surface 4a. Cam-disc 4 may be rotated to any desired setting by means of the combined knob and dial 5. On the opposite wall of the outer housing 1 and to one side is mounted the nipple block 6 of the flexible diaphragm assembly and held in place by nut 7 threaded thereon. Block 6 carries the lower wall 8 of the diaphragm assembly while the upper diaphragm wall 9 carries a stud 10 adapted to transmit pressure from the expansion of the diaphragm walls to a ball 11 as will later be described. The diaphragm walls are peripherally sealed and are adapted to separate and move stud 10 upwardly upon the ingress of fluid through the bore in block 6 as will be understood.

An inner housing 12 adapted to nest within the open end portion of outer housing 1 is formed with side walls 13 and 14 the latter of which has an inwardly offset, central portion 14a, a top wall 15 and a bottom wall 16 having an upwardly-turned portion 16a. Walls 15 and 16 are formed with oppositely disposed depressions 15b and 16b in which is journaled a hinge pin 17. The latter serves as a pivotal mounting for a bell-crank lever 18 having a centrally disposed, lower ear 19 and an opposite, upper flange 20 which extends across almost the full width of the inner housing 12. One end of a strip 21 of spring steel is united to flange 20 by means of rivets 22 and backing plate 23 and its other end is united to the end of cycling cam lever 24 by rivets 22 and backing plate 26. It will be understood that rivets 22 are repeated at intervals in the superposed portions of the united members (Fig. 1) to give permanent and secure connection of these parts.

Cycling cam lever 24 is generally triangular in shape and is stiffened by the formation of flanges 24a in its marginal edge portions. The left end of this lever narrows into a rectangular portion 24b and terminates in a cam-engaging portion 25, which like the flanges 24a is bent downwardly out of the general plane of the cam lever. A cylindrical cam 27 formed by moulding en bloc or by cutting an outer tube 27a to the outline shown in Figs. 1 and 2 and driving it tightly over a solid cylinder 28 which is mounted on a synchronously drive shaft 29, engages portion 25 of the cycling cam lever 24 during a half revolution of the cam and raises the left end of lever 24 through a distance equal to the height of the cam when the parts are arranged as shown in Fig. 2. A riser block 30 made, preferably of a rigid, insulating material and having a wall

31 of arcuate shape corresponding to its distance from hinge pin 17 is mounted on the cycling cam lever 24 by means such as rivets 32.

Normally closed switch contacts 33, 34 are mounted on a spring arm 35 and a conductor strip 36, respectively, and the assembly suitably insulated from and fixed to the wall 15 of the inner housing as by insulating spacers 37 and any desired means such as screws 38 and others (not shown) which may extend upwardly through insulating spacer blocks 39 from wall 15. I prefer to employ a pair of spaced, conductor strips 36 provided with terminal connections 40 and contacts 34 and bridge these contacts by means of a pair of electrically interconnected, similar contacts 33 fixed to the spring arm 35, thus providing two paths for the electric current between terminals 40.

Particular attention is directed to the shape of cam 27. While the inner margin of the tube portion 27a may have any desired shape depending on whether a straight line or other relationship is desired between the On and Off periods, in the preferred form, the tube 27a extends half way around the cylinder 28 at the longitudinal midpoint of the latter, thus giving equal On and Off intervals at this point. The leading edge 27b of the tube 27 is so inclined as to open the contacts 33, 34 during the optimum time interval, i. e. over at least one-half cycle of the A. C. power supply so that the circuit across the contacts will be broken as the current passes through zero. The inclination of cam edge 27b also corresponds to the slope of portion 25 of the cycling cam lever 24 and is preferably curved about the hinge pin 17 as a center so that the lifting force of the cam edge 27a is exerted in line with cam lever 24. The trailing edge 27c of the tube 27 is radial to the cam axis to produce rapid closure of the contacts. It is obvious that these functions of tube 27a and cylinder 28 with respect to the operation of the contacts could be interchanged if desired. The position of the lever portion 25 along the longitudinal axis of the synchronously rotated cam will, of course, determine for what part of a cam revolution the contacts 33, 34 are opened and closed. The factors and mechanism which determine the position of this lever in its "scanning" movement across the cam will next be described.

The upwardly turned portion 16a of bottom wall 16 is formed with a depression 16b which serves as a retainer for a coil spring 41 the other end of which seats in a depression 18a in the bell crank lever 18 to urge the latter counterclockwise (Fig. 1) to the position indicated by the dotted lines 18c, and rotate the cycling cam lever 24 to its full On position at the lower end of cylinder 28. This normally On position of lever 24 is subject to the influence of two other factors, viz: (1) the setting of the range dial 5 and (2) the pressure exerted by the diaphragm stud 10 as will now be described.

A diaphragm lever 42 located centrally of the inner housing 12 and outer housing 1 has a downwardly-inclined retaining aperture 43 for ball 11 which is held in its retained position by a flat, follow-up spring 44, the remote end of which is fixed to an intermediate portion of lever 42 by means of spacer 45 and rivet 46. A coil spring 47 somewhat weaker than spring 41 is centered beneath the floating lever 42 by the head of rivet

46 and its lower end is retained by a raised portion 13a of side wall 13 to bias lever 42 upwardly. The right end of floating lever 42 is offset downwardly from the portion just described and has fixed therein a hardened, pointed stud 48 in engagement with a hardened, disc-plate 49 fixed in the central portion of a wedge-shaped arm 18d which is normal to the major arm of bell crank 18 and integral therewith as shown in Fig. 1.

The left end of floating lever 42 is bent downwardly and then sharply up at 50 to provide an angular seat for a pair of knife edges 51, 52 formed on a pair of downwardly bent, spaced portions of a lever extension 53. The latter is fixed to a stiff spring strip 54 by means of rivets 55 which secure also a superposed, adjustable lever 56 having a slightly offset, left end 57 contacted by an adjustment screw 58 threaded through a boss 59 formed in the central portion 60 of lever extension 53 and accessible through an aperture (not shown) provided in the closed end wall of housing 1. The bent, spaced portions of lever extension 53 have marginal stops 61 which serve as guides for the floating lever 42. Rivets 62 and backing plate 63 serve to unite the strip 54 to the offset portion 14a.

It will be seen that lever 56 and its extension 53 provide a fulcrum constituted by the knife edges 51, 52 and adjustable vertically (Fig. 1) upon rotation of cam disc 4 and also easily calibrated to its zero setting by means of adjustment screw 58. Floating lever 42 is thus biased upwardly by spring 47 so that stud 48 always contacts disc plate 49, but since spring 47 is weaker than spring 41, the latter will rotate cycling cam lever 24 clockwise to its full On position with respect to cycling cam 27 until the remotely located, thermal feeler or pressure-responsive member (not shown) causes the diaphragm 8 to expand, moving the stud 10 and lever 42 upwardly, thereby slightly rotating cycling cam lever 24 in a clockwise direction toward the Off position.

The operation of my switch for electric range use, for example, is as follows: Assume that terminals 40 are connected in series with the power supply to energize an annular range heating unit and that nipple block 6 of the flexible diaphragm 8 is connected by a suitable conduit with a thermal bulb or feeler member located centrally of the heating unit as is shown, for example, by the Weber et al. Patent No. 2,303,012. The knob 5 is turned to the desired temperature setting for the particular cooking operation from its Off position wherein the highest and preferably stepped portion of cam 4a presses downwardly on lever 57 to maintain cycling cam lever 24 in its Off position at the upper end of cam 27. Rotation of cam 4a raises fulcrum knife edges 51, 52 so that spring 41 acting through bell crank 18 moves the cycling cam lever to full On position and moves the right end of lever 42 downwardly about the edges 51, 52 as a fulcrum since nipple block 6 in the cold position of diaphragm 8, 9 is ineffective as a fulcrum. As the heating unit raises the temperature of the cooking vessel to the setting of dial 5, the upward movement of diaphragm 8, 9 and of stud 10 raises the ball 11 and through it, the follow-up spring 44 and the right end of lever 42 to rotate the cycling cam lever 24 clockwise to an intermediate position on the cam 26 in which the heat supplied just equals the heat losses of the heated system.

In addition to its function of transmitting movement to the lever 42, follow-up spring 44 has

also a safety function in preventing possible damage to the cam-follower portion 25 of cycling cam lever 24. Thus, if the knob 5 is turned to the Off position from a previous temperature setting in which the cycling cam lever 24 has become stabilized in a position covering an intermediate portion of cam 26, the knife edges 51, 52 will move the left end 50 of lever 42 downwardly and move the right end thereof upwardly (Fig. 1) and its follower portion 25 against the straight, radial wall 21c of cam 27. The top of ball 11 will flex the follow-up spring 44 upwardly sufficiently to absorb the difference in height of cam 4a that was not utilized in moving follower portion 25 to the radial wall. This condition will continue until the rotation of cam 26 has brought the inclined wall 27a against the follower portion 25 raising the same so that it may snap to the fully Off portion of cam 27. Overshooting is prevented by engagement of bell crank 18 with the casing 16 as shown by the dotted line 64; similar engagement is indicated by dotted line 18c prevents overshooting of the cyclical cam lever 24 in the fully On position.

It will be apparent, of course, that portion 25 could be provided with a laterally upturned lip so that it would immediately surmount the radial wall 21c of cam 27. This arrangement would be inferior to that shown, however, since it would not provide the desired quick closure of contacts 33, 34 as portion 25 drops down over the radial cam wall at 27c (Fig. 1).

In addition to the greatly amplified movement of diaphragm 8, 9 and cam 4a provided by my lever arrangement and resulting in the relatively large, stabilizing excursion of follower 25 axially of cyclic cam 28 with consequent temperature control stability, other important features of my novel switch will be apparent. Cam 4 and adjustment screw 58 are in vertical alignment and only slightly offset from the knife edges 51, 52 so that bending stresses in levers 53 and 56 are minimized. Except for the stepped Off portion of cam 4a the entire 360 degree sweep of this surface may be utilized to spread the temperature range over a large, angular movement. Also the cam inclination need not be constant but may be steep through a narrow angle from the Off position to a low temperature, say 200 degrees F. permitting more than $\frac{3}{4}$ of the cam length to be utilized for the temperature range most used, from 200 to 500 degrees F. for example. The use of knife-edges and spring-biasing in the lever system eliminates lost motion and assures continued accuracy of calibration. While cam 26 is rotated at a uniform and preferably, slow speed, say one revolution per minute, as long as any of the four switches grouped thereabout are in On position (indicated by the radial arrows in Fig. 2) the form of switching means for the driving motor of this cam is not a part of this invention since various arrangements for this purpose will be obvious to those skilled in the art.

It will be apparent that the preferred form of my invention comprises a laterally movable cam lever having a follower portion which sweeps axially across a generally cylindrical, rotary switch actuating member, the lateral position of the former being dependent upon the indicated and desired temperatures of the heated body, and the surface of the member being divided into axially variable portions, certain of which together with the follower portion effect closure of the switch contacts and other portions of which similarly effect opening of said contacts. However,

other forms of my invention will be readily apparent.

Hence, instead of utilizing the cylindrical, stepped cam as the actuating means for the cycling cam lever 24, a rotary member corresponding to the hollow cam 27 could be used to raise the lever 24 and a transverse stop mounted on the left wall of the housing 1 (Fig. 2) could serve to limit the lower movement of said lever. Since the foregoing as well as other variations of my preferred form will be obvious to those skilled in the art, they have not been illustrated nor described in detail. However, I do not wish to be limited to the precise construction specifically disclosed as the preferred embodiment of my invention but only as may be fairly within the scope of the following claims:

1. A switch comprising normally closed electric contacts, a rotary cam having an outer cylindrical surface terminating in an axially inclined marginal wall substantially coextensive circumferentially with said surface and also normal thereto and the extremities of which are joined by a wall which is inclined to said surface and generally parallel to the axis thereof, a follower yieldably mounted to alternately engage said walls during the rotation of said cam and to be moved thereby into opening and closing relationship, respectively with said contacts and also pivotally mounted on an axis which is normal to the axis of said cam, pressure responsive means disposed beneath said follower and between said cam and pivotal mounting for moving said follower arcuately across said cam in a direction generally parallel to the axis of the latter whereby the duration of the open and closed conditions of said contacts will be a function of the pressure exerted by said means, and similarly disposed stop means spaced from said pressure responsive means for limiting the effectiveness thereof.

2. A switch comprising electric contacts, a rotary cam having an outer cylindrical surface terminating in an axially inclined marginal wall substantially coextensive circumferentially with said surface and the extremities of which are joined by an arcuate wall which is generally parallel to the axis of said surface, a follower yieldably mounted at its remote end to urge its opposite end into engagement with said walls alternately during the rotation of said cam and to be moved thereby into opening and closing relationship, respectively with said contacts, said follower being also pivotally mounted at the center of curvature of said arcuate wall, pressure responsive means disposed between said pivotal mounting and said cam for moving the opposite end of said follower about its pivotal mounting and across said cam in a direction generally parallel to the axis of the latter whereby the duration of the open and closed conditions of said contacts will be a function of the pressure exerted by said means.

3. The combination set forth in claim 2 wherein in said marginal wall is normal to said cylindrical surface, said arcuate wall is inclined thereto, and the cam engaging end of said follower is provided with a pair of surfaces having the same inclination as said walls insuring quick closing and opening, respectively of said contacts.

4. A switch comprising electrical contacts, a rotary cam having a circumferentially continuous, outer, cylindrical surface terminating in an axially inclined marginal wall substantially coextensive circumferentially with said surface and the extremities of which are joined by an

arcuate wall which is generally parallel to the axis of said surface, a casing disposed to one side of said cam and including parallel, top and bottom walls and a connecting end wall, contact carrying means carried by said top wall, a vertically disposed hinge extending through said parallel walls at the center of curvature of said arcuate wall, a follower yieldably mounted at its remote end to urge its opposite end into engagement with the walls of said cam alternately during the rotation of the latter and to be moved thereby into opening and closing relationship, respectively with said contacts, said follower being also pivotally mounted on said hinge, pressure responsive means disposed between said parallel walls for moving the opposite end of said follower about its pivotal mounting and across said cam in a direction generally parallel to the axis of the latter whereby the duration of the open and closed conditions of said contacts will be a function of the pressure exerted by said means.

5. A switch for electric heaters comprising electric contacts having open and closed positions, an elongated, pivotally mounted cycling lever including a cam follower portion and a transversely disposed, contact actuating portion, a cylindrical cam rotatable about an axis normal to the pivotal axis of said lever and having an axially variable, elevated portion corresponding to one of the positions of said contacts, and an inclined, uniformly stepped portion generally curved about the axis of said lever and adjacent said elevated portion for lifting said follower to the latter portion of said cam to produce uniform relative movement of said contacts, means including a relatively strong compression spring biasing said lever about its pivotal mounting in one direction, means including a relatively weak compression spring biasing said lever in the opposite direction, means responsive to the temperature of said heater for reinforcing said latter spring to move said lever in said latter direction, and a manually adjustable stop acting in opposition to said last-named means for limiting the movement of said lever in the latter direction whereby the open and closed intervals, respectively of said contacts will stabilize the energy supplied to said heater at the temperature corresponding to the adjusted position of said stop.

6. A switch for electric heaters comprising electric contacts having open and closed positions, a pivotally mounted cycling lever including a cam follower portion and a transversely disposed, contact actuating portion, a cylindrical cam rotatable about an axis normal to the pivotal axis of said lever and having an axially variable, elevated portion corresponding to one of the positions of said contacts and an inclined, uniformly stepped portion generally curved about the pivotal mounting of said lever and adjacent said elevated portion for lifting said follower to the latter portion of said cam to produce uniform relative movement of said contacts, means including a relatively strong compression spring biasing said lever about its axis in one direction, an adjustable lever providing a shiftable fulcrum adjacent one end thereof, a floating lever having one end fulcrumed thereon and the opposite end in force transmitting relation to said cycling lever, means including a relatively weak compression spring biasing said floating and cycling levers in opposition to said first-mentioned compression spring, means responsive to the temperature of said heater for reinforcing said relatively weak spring to

move said last mentioned levers against the force of said relatively strong spring, and a manually adjustable stop adapted to engage said adjustable lever to determine the position of such fulcrum.

7. A switch for electric heaters comprising electric contacts having open and closed positions, a pivotally mounted cycling lever including a cam follower portion and a transversely disposed, contact-actuating portion, a cylindrical cam rotatable about an axis normal to the pivotal axis of said lever and having an axially variable, elevated portion corresponding to one of the positions of said contacts and an inclined, uniformly stepped portion curved about the pivotal mounting of said lever and adjacent said elevated portion for lifting said follower to the latter portion of said cam to produce uniform relative movement of said contacts, means including a relatively strong compression spring biasing said lever about its axis in one direction, an adjustable lever providing a shiftable fulcrum adjacent one end thereof, an apertured floating lever having one end fulcrumed thereon and the opposite end in force transmitting relation to said cycling lever, means including a relatively weak compression spring biasing said floating and cycling levers in opposition to said first-mentioned compression spring, a spring-pressed ball seated in said aperture, means responsive to the temperature of said heater and adapted to engage said ball for reinforcing said relatively weak spring to move said last mentioned levers against the force of said relatively strong spring, and a manually adjustable stop adapted to engage said adjustable lever to determine the position of said fulcrum.

8. A switch comprising normally closed electrical contacts, a rotary cam having an outer cylindrical surface terminating in an axially inclined marginal wall substantially co-extensive circumferentially with said surface and the extremities of which are joined by a wall which is generally parallel to the axis of said surface, a bell crank lever pivotally mounted about an axis normal to the axis of said cam and having an elongated flange extending parallel to the axis of said cam and an arm below said flange and extending toward said cam, an elongated, resilient strip carried by said flange, a rigid, generally triangular cam follower having a base co-extensive with said strip and united thereto and a narrow apical portion adapted to alternately engage said walls during the rotation of said cam and to be moved thereby into opening and closing relationship, respectively with said contacts, pressure responsive means disposed beneath said cam follower for moving the latter arcuately across said cam in a direction generally parallel to the axis of the latter whereby the duration of the open and closed conditions of said contacts will be a function of the pressure exerted by said means.

9. A switch comprising electric contacts having open and closed positions, a rotary cam having an inner cylindrical surface, a radially spaced outer cylindrical surface, an axially inclined marginal wall substantially co-extensive circumferentially with said latter surface and having terminal portions spaced longitudinally thereof, and a curved marginal wall uniting said portions, said walls being disposed between said surfaces and serving to define said latter surface, a follower for changing the relative positions of said contacts, said follower being pivotally mounted at the center of curvature of said latter marginal wall about an axis which is normal to the axis of

said surfaces and also yieldable radially of said surfaces to alternately engage the latter and to be moved from said inner surface to said outer surface by engagement with said curved marginal wall, and pressure responsive means for moving said follower arcuately across said cam about said pivotal mounting whereby the duration of the open and closed conditions of said contacts will be a function of the pressure exerted by said means.

10. A switch comprising electric contacts having open and closed positions, a rotary cam having an inner, cylindrical surface, a radially spaced, outer cylindrical surface, a radially disposed, axially inclined, marginal wall substantially co-extensive circumferentially with said latter surface and having terminal portions spaced longitudinally thereof and a curved, non-radial marginal wall uniting said portions, said walls being disposed between said surfaces and serving to define said latter surface, a follower for changing the relative positions of said contacts, said follower being pivotally mounted at the center of curvature of said latter marginal wall about an axis which is normal to the axis of said surfaces and also yieldable radially of said surfaces to alternately engage the latter and to be moved from said inner cylindrical surface to said outer cylindrical surface by engagement with said curved, marginal wall, and pressure responsive means for moving said follower arcuately across said cam about said pivotal mounting whereby the duration of the open and closed conditions of said contacts will be a function of the pressure exerted by said means.

11. A switch comprising normally closed electrical contacts, an elongated arm carrying one of said contacts and having an overhanging portion, a rotary cam having an inner cylindrical surface, a radially spaced outer cylindrical surface, an axially inclined marginal wall substantially co-extensive circumferentially with said latter surface and having terminal portions spaced longitudinally thereof, and a curved marginal wall uniting said portions, said walls being disposed between said surfaces and serving to define said latter surface, a follower pivotally mounted at the center of curvature of said latter marginal wall about an axis which is normal to the axis of said surfaces and also yieldable radially of said surfaces to alternately engage the latter and to be moved from said inner surface to said outer surface by engagement with said curved marginal wall, means integral with said follower for moving said elongated arm at any pivotal position of said follower and pressure responsive means for moving said follower arcuately across said cam about said pivotal mounting whereby the duration of the open and closed conditions of said contacts will be a function of the pressure exerted by said means.

12. A switch comprising electric contacts having open and closed positions, a rotary cam having an inner, cylindrical surface, a radially spaced, outer cylindrical surface, a radially disposed, axially inclined, marginal wall substantially co-extensive circumferentially with said latter surface and having terminal portions spaced longitudinally thereof and a curved, non-radial marginal wall uniting said portions, said walls being disposed between said surfaces and serving to define said latter surface, a follower for changing the relative positions of said contacts and having a cam engaging portion of the same non-radial inclination as said curved, mar-

ginal wall, said follower being pivotally mounted at the center of curvature of said latter marginal wall about an axis which is normal to the axis of said surfaces and also yieldable radially of said surfaces to alternately engage the latter and to be moved from said inner cylindrical surface to said outer cylindrical surface by engagement with said curved, marginal wall, and pressure responsive means for moving said follower arcuately across said cam about said pivotal mounting whereby the duration of the open and closed conditions of said contacts will be a function of the pressure exerted by said means.
